UNITED STATES PATENT OFFICE.

MAXIMILIAN J. KOENIG, OF JERSEY SHORE, PENNSYLVANIA.

FOLDING HEAD-REST.

SPECIFICATION forming part of Letters Patent No. 319,980, dated June 16, 1885.

Application filed August 2, 1884. (No model.)

To all whom it may concern:

Be it known that I, MAXIMILIAN J. KOENIG, a citizen of the United States, residing at Jersey Shore, in the county of Lycoming and State 5 of Pennsylvania, have invented certain new and useful Improvements in Folding Head-Rests, of which the following is a specification, reference being had therein to the accompanying drawings.

10 This invention has relation to improvements in head-rests, and the same is an improvement on a similar patent granted to me on the 18th day of December, 1883, and numbered 290,644; and the invention consists in the construction 15 and novel arrangement of the various parts of which it is composed, all as will be herein-after more fully explained, and particularly pointed out in the claim appended.

The annexed drawings, to which reference 20 is made, fully illustrate my invention, in which Figure 1 represents a perspective view of my folding head-rest. Fig. 2 is a side view of the same, and Figs. 3, 4, 5, and 6 are detail views.

Referring by letter to the accompanying 25 drawings, A designates the folding head-rest, consisting of the head portion *a*, made in skeleton form and divided at the center into two parts, *b* and *c*, which are hinged to one another, as at *d*, and the same is perforated around 30 its edges, as shown at *e*, to receive the stitches or fastenings which secure the cushion thereto.

B B represent the arms of the device, which are constructed alike, the upper sections *f* of which are provided with T-shaped lugs *g*, 35 which connect with the slots *h* on the head portion, whereby said head-rest is removably applied to the arms aforesaid. This upper sec-

tion is bent at right angles to the vertical portion, as shown at *i*, and to the lower end, *j*, of which is pivoted the second section, *k*, and to 4 the lower ends of the second sections are pivoted the third or last section, *l*, as at *m*. These latter sections are provided with lugs *n*, that engage notches *o* in the adjoining sections, which serve as stops for the arms when the 4 latter are unfolded for use.

C indicate the straps by means of which the device is secured to the wearer.

It will be seen from the above description and by reference to the annexed drawings that 5 the head-rest can be detached from the arms and folded, and that the arms can also be folded section upon section and stored in a very small space, and it is durable, light to carry, and at the same time cheap to manufacture.

Having thus described my invention, what I claim, and desire to secure by Letters Patent, is--

The herein-described head-rest, consisting 6 of the perforated head portion *a*, divided into sections *b* *c*, and hinged to one another and having the slots *h* *h*, the pivoted arms B B, the upper section, *f*, having the T-shaped lugs *g* *g*, adapted to engage the slots in the head portion, and provided with the securing-straps C C, the whole constructed and arranged as shown and described.

In testimony whereof I affix my signature in presence of two witnesses.

MAXIMILIAN J. KOENIG.
